UNITED STATES PATENT OFFICE.

WALTER P. MURPHY, OF CHICAGO, ILLINOIS.

SHEET-METAL END STRUCTURE FOR RAILWAY-CARS.

1,311,572.

Specification of Letters Patent. Patented July 29, 1919.

Application filed August 29, 1913. Serial No. 787,831.

To all whom it may concern:

Be it known that I, WALTER P. MURPHY, a citizen of the United States, residing at Chicago, in the county of Cook and State 5 of Illinois, have invented certain new and useful Improvements in Sheet-Metal End Structures for Railway-Cars, of which the following is a specification.

My invention relates to metal end structures for railway cars, and has as its object the provision of certain improvements in sheet metal structures for railway cars that will not be subject to the present difficulties in manufacturing sheet metal end structures and one in which the durability and strength for resisting the various stresses to which structures of the above character are subjected will be increased.

More specifically, it is the object of the invention to provide a corrugated end structure that will present certain economic advantages of manufacture over the types of corrugated end structures in which the ends of the corrugations terminate within the edges of the end sheets and also have structural features which will increase its strength for resistance against the thrusts of the cargo against the car end, caused by the sudden starting or stopping of the car. The metal end structures referred to, in which the corrugations terminate short of the end of the sheet, while being practical, are more expensive to manufacture than the structure in which the corrugations extend to the end of the sheet, as they require expensive dies between which the sheets, after being heated, are pressed, while in the latter case the corrugated sheets may be formed by the well known rolling process in which the cold metal may be formed into sheets of one or more stock sizes and afterward sheared off, if necessary, to fit the car to which it is intended to be applied.

A further object of the invention is to provide means for securing the end sheets together and to the car frame that will rigidify the frame and will provide water-proof joints between the end sheet and the car frame.

The invention has as further objects the arrangement, construction and combination of parts hereinafter more specifically described and claimed.

The preferred embodiment of my invention is illustrated in the accompanying

drawings, in which similar characters of reference designate corresponding parts, and in which—

Figure 1 is an end elevation of a railway box car showing my improved metal end structure applied thereto;

Fig. 2 is a sectional view taken on line 2—2 of Fig. 1;

Fig. 3 is a sectional plan taken on line 3—3 of Fig. 1;

Figs. 4, 5 and 6 are detail views, in perspective, of the corrugated girth members looking at the inside thereof;

Fig. 7 is a fragmentary view, in elevation, of a modified form of my invention; and

Fig. 8 is a sectional view taken on line 8—8 of Fig. 7, looking in the direction of the arrows.

Referring to the drawings and particularly to Figs. 1 to 6, inclusive, the end structure is shown as composed of an upper sheet 25 and a lower sheet 26 provided with vertical corrugations or ribs 27 and 28, respectively. The vertical edges of the end sheet are bent at right angles so as to form flanges 29 and 30 which overlap the side sheathing 31 of the car and are secured to the car by means of bolts 32 which preferably extend through the side sheathing 31 and the corner post 33 of the car frame. Secured to the end plate 34 is a reinforcing or girth member 35 which is effectively a part of the end plate of the car; extends from side to side of the same and is provided with a corrugation or rib 36. The corrugation or rib 36 of the reinforcing or girth member is shown as being deepest at the center, as at 37, and tapering down and terminating short of the end so as to provide a comparatively wide attaching flange 38 which is secured to the side plate 39 by means of bolts 40. The reinforcing member or girth 35 is provided with flanges 41 and 42, the former of which extends up under the fascia plate 43 so as to prevent water from working in between the flange and wooden end plate, and is secured to the said wooden end plate by means of bolts 44.

The lower flange is formed with corrugations 45 which fit over the corrugations 27 at the upper edge of the sheet 25, the sheet being secured thereto by rivets 46. The girth member when attached to the car in this manner strengthens the wooden end plate and also more securely binds the side plate to the end plate and corner posts. In fact,

if made heavy enough it could take the place of the end plate, making a wooden plate unnecessary. The sheets 25 and 26 may be secured together in any suitable manner, for example, by the lap joint 47 in which the upper sheet overlaps the lower sheet and forms a stiffening strip across the end. To further strengthen the end at the point of jointure of the sheets I preferably provide a girth member 48 which is provided with a corrugation 49 similar to the one shown on the reinforcing member or top girth 35. Both of the flanges 50, 51 of the girth 48 are corrugated so as to fit into the corrugations 27 of the upper sheet 25, the angular flanges 52, extending around the corner of the car, and are secured thereto by the bolts 32^a which extend through both flanges 29, 30 of the end sheets and through the corner post. At the lower edge of the car end I preferably provide another transverse reinforcing member or girth 53 provided with angular flanges 54 secured to the corner post and with a strengthening rib 55. The lower web 56 of the strengthening rib preferably extends between the flooring 57 and the end sill 58 and is secured to the latter by bolts 59. The upper web 60 of the rib 55 is formed with a flange 61 which is provided with corrugations adapted to fit over the corrugations 28 of the lower end sheet 26 and is secured thereto by rivets 62 which are spaced close enough together to provide a water-tight joint. The lower edge of the end sheet 26 preferably extends down below the upper edge of the flooring 57 and the forward edge of the floor plank 57^a is formed with rounded portions 63 which fit into the concavities formed by the corrugations 28 so as to prevent any portion of the cargo, when it is composed of grain or the like, from entering the corrugation 55 and thereby causing difficulty to remove it. The corrugations or ribs 36, 49 and 55 of the girth members preferably extend transversely of the corrugations in the end sheet. While the corrugations alone may be strong enough to withstand the ordinary thrusts of any heavy cargo such as T-rails, lumber or the like, against the car, caused by the sudden starting or stopping of the car, the car end is often subjected to unusually hard shocks due to the universal practice of trainmen in making up the trains in the railway yards, in which the car is either run down an inclined track or given a start by the locomotive and then released therefrom and permitted to bump into the cars previously switched or placed on the branch track on which the particular train is being made up. It will be seen that by having the stiffening corrugations 36, 49 and 55 extending transversely of the corrugations of the end sheets from side to side of the car and by having the end sheets secured directly to one of their flanges, the girth

members will receive a portion of any shock that may occur at any particular point of the sheet, that is, the corrugation or rib 55 would receive the shock when it occurred at the lower part of the car and would divide the stresses between the two corner posts and end sill. By having the upper edge of the end sheet 25 secured to the flange 42 of the girth 35 the same results are obtained when the thrust occurs near the top of the car, as in cases when the car is loaded with lumber.

In Figs. 7 and 8 of the drawing, I have illustrated modified forms of transverse reinforcing or girth members 35^a, 48^a and 53^a. In the modified forms the corrugations 35^b, 48^b and 53^b extend around the corner of the car and terminate a short distance within the end of the attaching flange, shown best in Fig. 8. This structure strengthens the corner of the car and by having the corrugations terminating as shown prevents the rain and dirt from being driven into the corrugations, which would corrode and weaken the members in which these are pressed.

While I have illustrated my invention in certain preferred embodiments, it will be understood that further modifications might be made, within the scope of the claims herein, without departure from the spirit of the invention.

What I claim is:

1. The combination with a railway car, of a sheet metal end structure comprising an end sheet formed with vertical corrugations and with vertical flanges adapted to be secured to the side of the car, and girth members overlapping each of the horizontal edges of said sheet and provided with angular flanges adapted to be secured to the side of the car.

2. The combination with a railway car, of a sheet metal end structure comprising an end sheet formed with vertical corrugations extending to the edges of said sheet and with vertical flanges adapted to be secured to the side of the car, and girth members engaging the horizontal edges of said sheet and provided with angular flanges adapted to be secured to the side of the car.

3. The combination with a railway car, of a sheet metal end structure comprising an end sheet formed with vertical corrugations and with vertical flanges adapted to be secured to the body of the car, and a horizontal girth member adapted to fit into said corrugations and provided with flanges adapted to be secured to the side of the car.

4. The combination with the end plate of a railway car, of a sheet metal end structure comprising an end sheet formed with vertical corrugations extending to the edges of the sheet, and a girth member extending from side to side of the car and provided with a flat flange adapted to be secured to

90

95

115

120

125

130

said end plate and formed with a corrugated flange adapted to be secured to said end sheet.

5. The combination with the end plate of 5 a railway car, of a sheet metal end structure comprising an end sheet formed with vertical corrugations extending to the edges of the sheet and formed with vertical angular flanges adapted to be secured to the side of the car, and a girth member extending from side to side of the car and provided with flat flanges adapted to be secured to said end plate and to the side of the car and formed with a corrugated flange adapted to be secured to the upper edge of said end sheet.

6. The combination with a railway car, of a sheet metal end structure comprising an end sheet formed with vertical corrugations coterminous with the sheet and with 20 vertical angular flanges adapted to be secured to the side of the car, and girth members extending from side to side of the car and provided with corrugated attaching flanges adapted to fit over the corrugated 25 edges of said sheet, said girth members being provided with corrugations extending transverse to the corrugations of said end sheet.

7. The combination with a railway car, of 30 a sheet metal end structure comprising an end sheet formed with vertical corrugations and with vertical angular flanges adapted to be secured to the side of the car, and girth members extending from side to side of the car and provided with corrugated attaching flanges adapted to fit over the corrugated 35 edges of said sheet, said girth members being provided with corrugations extending transverse to the corrugations of said end sheet 40 and which terminate within the ends of said girth members.

8. The combination with the end sill of a railway car, of a metal end structure comprising an end sheet formed with vertical 45 corrugations which extend to the edges of the sheet, and a girth member provided with a corrugation which extends from side to side of the car and provided with a flange formed with corrugations adapted to be secured to the end sheet and with a flat extension 50 adapted to be secured to said end sill.

9. The combination with the end sill and flooring of a railway car, of a metal end structure comprising an end sheet formed 55 with vertical corrugations which extend to the edges of the sheet, and a girth member provided with a corrugation which extends transverse to the corrugations of the end sheet from side to side of the car and provided with an angular flange formed with corrugations adapted to be secured to the 60 end sheet and with an extension adapted to extend between the end sill and the flooring and be secured to said end sill, said flooring 65 being formed with a configuration adapted

to fit into the concavities formed by the corrugations of said sheet.

10. The combination with the end plate, corner posts and end sill of a railway car, of a metal end structure comprising an end sheet formed with vertical corrugations extending to the edges of the sheet and with vertical flanges adapted to be secured to the corner posts, and upper and lower girth members formed with horizontal stiffening 70 ribs, said girth members being provided with flat flanges adapted to be secured to said end plate and end sill, respectively, and provided with corrugated flanges adapted to be secured to the edges of said end sheet. 80

11. In a metal end structure for railway cars, the combination with the framing of the car, of a plurality of metal end sheets provided with vertical corrugations and with flanges adapted to be secured to the 85 car, an upper and lower member adapted to be secured to the car and provided with angular flanges adapted to be secured to the end sheets, and a girth member extending from side to side of the car at the point 90 of jointure of said sheets.

12. A metal end for a railway car comprising a vertically corrugated sheet, the corrugations extending to the edges of the sheet, and a girth member arranged transversely 95 thereof and secured thereto, said girth member being corrugated longitudinally and being provided with transverse corrugations adapted to be fitted and secured to the vertical corrugations of said sheet, said end having flat edge flanges for attachment to the car. 100

13. In a railway car, a metal end structure comprising a vertically corrugated sheet secured by its side edges to the car, the corrugations extending to the edges of the sheet, and a plurality of girth members arranged transversely thereof, said girth members being longitudinally corrugated and being provided with one or more flanges 105 transversely corrugated to fit the vertical corrugations of said sheet, said transverse members being secured to said sheet and one of said transverse members being secured to the end sill of the car by angular flat flanges 110 formed on them. 115

14. A sheet metal end structure for a railway car comprising a plurality of overlapped end sheets formed with corrugations extending to the edges of the sheets, and 120 members extending transversely to the corrugations of said sheets between the sheets and at the edges thereof, which members are formed with corrugations extending lengthwise of the same and with corrugations fitting the corrugations of the end sheets. 125

15. A sheet metal end structure for a railway car comprising a pair of end sheets formed with corrugations extending to the 130 edges of the sheets and arranged with their

adjacent edges overlapped, and a connecting member for the sheets which is corrugated to fit the corrugations of said sheets.

16. A sheet metal end structure for a railway car, comprising a plurality of end sheets, and a plurality of parallel members arranged between the sheets and at the edges thereof for connecting the same together and to the car, said members being longitudinally and transversely corrugated.

17. A sheet metal end structure for a railway car comprising a plurality of end sheets, and a plurality of parallel members arranged between the sheets and at the edges thereof for connecting the same together and to the car, said end sheets being formed with corrugations and the parallel members with corrugations extending transversely to the corrugations of the sheet.

20 18. In a railway box car the combination with the side walls of the car, of a wooden end plate, a metal stiffening member secured to said end plate, extending across the car from side to side, anchored to the side walls of the car and formed with a corrugation extending lengthwise of the same and a fascia plate conformed to the slope of the roof and overlapping the upper flange of said metal stiffening member.

30 19. The combination with the side walls, end sill and flooring of a railway car, of a metal end sheet and a metal stiffening member extending across the car from side to side, secured to the side walls of the car and to the lower edge of said end sheet, and formed with a corrugation extending lengthwise of the same and with a flange which intervenes between the flooring of the car and the end sill and is secured to the latter.

40 20. The combination with the under frame and side walls of a railway box car, of an end plate comprising a metal member extending across the car from side to side, anchored to the side walls thereof and formed

45 with a rigidifying element projecting from the plane of said member, a transverse metal member extending across the car from side to side adjacent the under frame, anchored to the side walls of the car and formed with a rigidifying element projecting from the plane of said member, and a sheet metal end wall structure extending between and secured at its edges to said stiffening members at the top and bottom of the car, and to the side walls of the car, and provided with vertical corrugations.

50 21. The combination with the under frame and side walls of a railway box car, of an end plate comprising a metal member extending across the car from side to side, anchored to the side walls thereof and formed with a rigidifying element projecting from the plane of said member, a transverse metal member extending across the car from side to side adjacent the under frame,

anchored to the side walls of the car and formed with a rigidifying element projecting from the plane of said member, and a sheet metal end wall structure extending between and secured at its edges to said stiffening members at the top and bottom of the car, and to the side walls of the car, and provided with vertical corrugations which extend substantially from one of said rigidifying elements to the other.

70 22. The combination with the under frame and side walls of a railway box car, of an end plate comprising a metal stiffening member extending across the car from side to side, anchored to the side walls and formed with a corrugation lengthwise thereof, a metal stiffening member adjacent the under frame of the car, anchored to the side walls thereof and formed with a corrugation extending lengthwise of the same, and a sheet metal end wall structure extending between and secured to said metal stiffening members, and to the side walls of the car and provided with vertical corrugations which extend from substantially the top to the bottom of said structure so that stresses thereon are transmitted to the transverse corrugations of said stiffening members.

75 23. In a car end construction, the combination with the corner posts and wooden end plate, of a substantially horizontal strengthening member of channeled cross-section, externally arranged opposite the end plate.

80 24. In a car end construction, the combination with the corner posts, end sill and wooden end plate, of a substantially horizontal strengthening member of channeled cross-section, externally arranged opposite the end plate, and vertically corrugated metal elements which rigidify the end construction between the end plate and the sill of the car.

85 25. In a railway car, the combination of an end plate, an end-closure plate extending downward from said end plate and having a plurality of strengthening ribs therein extending in vertical position from substantially the lower edge of the end plate, and means for bracing said end-closure plate relative to said end plate comprising a strengthening rib extending in horizontal position along said end plate and secured thereto, whereby said horizontally-extending strengthening rib and said vertically-extending strengthening ribs mutually reinforce each other.

90 26. In a railway car, the combination of an end plate, an end sill, an end-closure plate extending from said end sill to said end plate and having a plurality of strengthening ribs therein extending in vertical position from substantially the lower edge of the end plate to the upper edge of the end sill, means for securing the lower

end of the end-closure plate to said end sill, and means for bracing said end-closure plate relative to said end plate, comprising a strengthening rib extending in horizontal 5 position along the outer face of said end plate and secured at intervals to said end plate whereby said end-closure plate is prevented from bowing outward between its side edges relative to said end plate, said

horizontally-extending rib and said vertically-extending ribs being adapted to mutually reinforce each other for strengthening the end structure. 10
